UNITED STATES PATENT OFFICE.

WALTER JENKINSON, OF PHILADELPHIA, AND JOHN L. WHEELER, OF ROXBOROUGH,
PENNSYLVANIA.

METHOD OF PREPARING PIPE COILS FOR CASTING.

Application filed March 19, 1924. Serial No. 700,316.

This invention relates to a method of preparing pipes around which blocks of metal are to be cast, and more particularly to a method of packing copper pipe in the form of a coil, around which blocks or contact members are to be cast in the forming of electrode holders such as shown and described in the Johnson Hughes Patent No. 1,335,895, dated April 6, 1920.

10 The object of the present invention is to provide an improved method of packing pipe coils and other pipe forms with sand, whereby they are packed solid so as to prevent collapsing of the pipe walls during 15 the casting of molten metal therearound.

In the drawings, Figure 1 shows one form of apparatus used in carrying out the method of this application.

Figure 2 is a plan of a pipe having contacts cast therearound as used in electrode holders similar to that described in the Johnson Hughes Patent No. 1,335,895, of April 6, 1920.

Referring more particularly to the drawings, the letter A designates the pipe coil as a whole, which is to be packed with sand prior to the casting of the blocks or contacts 2 around the same, to form the finished coil of Figure 2.

25 In carrying out the method of this invention, the one end of the coil A is provided with a suitable cap 3 having a vent opening 4 therein, and the other or open end is connected by a pipe union coupling member 5 with a pipe 6, having a connection intermediate its ends with a sand supply pipe 7 which communicates at its upper end with a hopper 8 having a slide valve 9 for regulating the flow of sand through the pipe 7.

40 The upper end of the pipe 6 is connected to a compressed air supply pipe 10 having a regulating valve 11 mounted intermediate its ends.

45 The steps of this improved method may be somewhat varied, the main and controlling steps being the loading of a quantity of sand into the coil, and then packing the sand therein by compressed air or other fluid.

In carrying out this method the cap 3 may be applied and the coil filled as nearly 50 as possible with sand prior to its connection with the pipe 6. Then the pipe 6 may be filled with sand from the hopper 8, and then the valve 11 may be opened to permit the compressed air from the pipe 10 to pack the sand into the coil A, this operation being repeated until the coil is filled.

Another way of carrying out the invention is to apply the cap 3 to one end of the coil A and connect the other end of the coil to the pipe 6, then to open the valve 9 on the hopper 8 and permit the sand to flow into the coil and pipe 6, then to close the valve 9 and to open the valve 11 and permit the compressed air from the pipe 10 to pack the sand into the coil A, then to close the valve 11 and again open the valve 9 to cause a fresh supply of sand to flow into the coil A and pipe 6, then again close the valve 9 and open the valve 11 to again allow the 70 compressed air to flow from pipe 10 into the coil and pack the new supply of sand and repeating said operations until the coil is filled with packed sand.

Other variations of the methods herein 75 described may be practiced, but the controlling step of packing the sand into the coil by fluid pressure will remain the same.

We claim—

The method of preparing copper pipe 80 coils around which contacts are to be cast in forming electrode holders, which consists in closing one end of said coil with the exception of a small vent opening, loading a quantity of sand into said coil through 85 its open end, then passing fluid under pressure into said pipe coil through its open end to pack the sand, and repeating said operations until said pipe coil is full of sand.

In testimony whereof, we have hereunto 90 set our hands.

WALTER JENKINSON.
JOHN L. WHEELER.
